PACKAGE OF COTTON SWABS OR THE LIKE

Werner Kistler, 8737 Gommiswald,
St. Gall, Switzerland

Filed Oct. 12, 1966, Ser. No. 4,257

Claims priority, application Switzerland May 10, 1966

Term of patent 14 years

Int. Cl. D9—06

U.S. Cl. D9—187

FIG. 1

FIG. 2

FIG. 3

FIG. 4

FIG. 1 is a front elevational view of a package of cotton swabs or the like, showing my new design;

FIG. 2 is an elevational view looking from the right of FIG. 1 with two cotton swabs removed from one end to illustrate the swab receiving grooves;

FIG. 3 is an enlarged fragmentary view showing a portion of the internal holding plate and two cotton swabs;

FIG. 4 is a sectional view taken on the line 4—4 of FIG. 3; and

FIG. 5 is a sectional view taken on the line 5—5 of FIG. 3.

I claim:

The ornamental design for a package of cotton swabs or the like, as shown.
